Primary Examiner — Austin Murphy(74) *Attorney, Agent, or Firm* — Leason Ellis LLP(57) **CLAIM**

The ornamental design for a head-mounted display device, as shown and described.

DESCRIPTION

FIG. 1 is a top, right-side perspective view of a head-mounted display device showing our new design;
 FIG. 2 is a left side elevation view thereof;
 FIG. 3 is a right-side elevation view thereof;
 FIG. 4 is a top plan view thereof;
 FIG. 5 is bottom plan view thereof; and,
 FIG. 6 is a front elevation view thereof; and,
 FIG. 7 is a rear elevation view thereof.

The broken lines in the drawings represent portions of the head-mounted display device that form no part of the claimed design.
